Primary Examiner — Rhea Shields*(74) Attorney, Agent, or Firm* — Moser Taboada(57) **CLAIM**

The ornamental design for an electric battery, as shown and described.

DESCRIPTION

1. Batteries, electric

1.1 is a perspective view of a electric battery embodying the new design;

1.2 is a side view of the design of 1.1;

1.3 is a front view of the design of 1.1; and

1.4 is a top view of the design of 1.1.

In the reproductions, the broken lines are for the purpose of illustrating environment only and form no part of the claimed design.

1 Claim, 4 Drawing Sheets(56)
